CLAIM

The ornamental design for a clip for securing electrical wiring, as shown and described.

DESCRIPTION

FIG. 1 is a front elevational view of a clip for securing electrical wiring showing our new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof;
FIG. 7 is a top front perspective view thereof; and,
FIG. 8 is a top rear perspective view thereof.
